(57) **CLAIM**

The ornamental design for a vacuum cleaner nozzle, as shown and described.

DESCRIPTION

1. Vacuum cleaner nozzle

1.1 : Front perspective view

1.2 : Bottom perspective view

1.3 : Front

1.4 : Back

1.5 : Left

1.6 : Top

1.7 : Bottom

This article is used for suction in a vacuum cleaner; a right view is omitted because it is a mirror image of the left view; the broken lines depict portions of the vacuum cleaner nozzle that form no part of the claimed design; the shading lines are used to show the surface of the claimed design and do not represent its surface ornamentation.
